UNITED STATES PATENT OFFICE.

IRA F. LAMP, OF GRIFFITHSVILLE, WEST VIRGINIA.

FOLDING CRATE.

1,206,719.

Specification of Letters Patent. Patented Nov. 28, 1916.

Application filed November 23, 1915. Serial No. 63,086.

To all whom it may concern:

Be it known that I, IRA F. LAMP, a citizen of the United States, residing at Griffithsville, in the county of Lincoln and State 5 of West Virginia, have invented new and useful Improvements in Folding Crates, of which the following is a specification.

This invention relates to folding crates and especially to crates used for the trans-10 portation of chickens and other fowls.

One object of the invention is to produce a crate which when in use for the transportation of fowls, produce and the like will be of ample capacity and which, when folded 15 or collapsed for reshipment will occupy the smallest possible cubic area.

A further object of the invention is to produce a folding crate of simple and improved construction the parts of which are 20 so arranged and connected together as to make the contents easily available for examination or for filling and emptying the crate.

With these and other ends in view which 25 will readily appear as the nature of the invention is better understood, the same consists in the improved construction and novel arrangement and combination of parts which will be hereinafter fully described and partic-30ularly pointed out in the claims.

In the accompanying drawings has been illustrated a simple and preferred form of the invention, it being, however, understood that no limitation is necessarily made to the 35 precise structural details therein exhibited, but that changes, alterations and modifications within the scope of the claims may be resorted to when desired.

In the drawings,—Figure 1 is a top plan view showing the improved crate extended for use. Fig. 2 is a longitudinal vertical section taken on the line 2—2 in Fig. 1. Fig. 3 is a vertical transverse section taken on the 40 line 3—3 in Fig. 1. Fig. 4 is a plan view showing the crate partly collapsed. Fig. 5 is a transverse sectional view taken on the line 5—5 in Fig. 4. Fig. 6 is a perspective view showing the crate collapsed for trans-45 portation. Fig. 7 is a perspective view 50 showing the crate extended for use.

Corresponding parts in the several figures are denoted by like characters of reference.

The improved crate comprises in its construction a bottom member A, side members 55 B, B', end members C, C, and a top member

D, which latter may also be regarded as constituting a lid or cover.

The bottom member is divided longitudinally to form two wings 15 which are connected together by hinges 16 at the lower 60 edges of their meeting faces. Each side member B, B', is composed of two wings, 18, said wings being connected together by hinges 19 secured on the outer faces of the 65 respective wings along the meeting edges thereof so as to enable the said wings to be folded together. Each end member C is composed of upper and lower wings 20, 21 which are connected together by hinges 22 70 disposed on the outer faces of said wings along the meeting edges thereof. The upper wing 20 of each end member is connected with the upper wing 17 of the side member B by means of hinges 23 secured on the inner faces of the respective members 20 and 17, enabling the end members, when folded or collapsed, to be folded on the inner face 75 of the top wing 17 of the side member B with which they are connected. The top 80 member or lid D is hingedly connected with the top wing of the other side member B', as will be presently more fully described.

The top member D is composed of two wings, one of which, 24, extends the full 85 length of the crate, while the other wing 25 is materially shorter than its mate with which it is connected by means of hinges 26 secured on the top faces of the respective wings. Hingedly connected with the wing 90 25 at one end of said wing is an auxiliary lid 27 which may be operated independently for placing poultry or removing it from the crate. The hinges 28 which connect the auxiliary lid 27 are secured on the top faces 95 of said wing and auxiliary lid. The short wing 25 of the top member D is connected with the side member B' by means of hinges 29 which are secured on the inner faces of the respective members which may thus be 100 folded together. Hooks and eyes 30, 31 are provided whereby the upper wings 20 of the end members C may be connected with the upper wing 17 of the side member B', and similar hooks and eyes 30' and 31' are pro-105 vided to connect the lower wings 21 of the end members C with the bottom member when the crate is extended for use, these being the only fastening members required to maintain the crate in extended position, it 110

being, of course, understood that any well known and appropriate fastening means may be substituted for the hooks and eyes. Fastening means consisting of a hook 32 and 5 an eye 33 have also been shown for the purpose of connecting the free edge of the lid or top member with the top edge of the side member B for the purpose of securing the lid in closed position. No fastening means 10 has been shown for the auxiliary lid 27, but such means may be provided if desired.

The wings of the bottom member A have been shown as being constructed of solid material and the wings of the side members, 15 the end members and the top member, as well as the auxiliary lid, have been shown as constructed of lattice-work, thereby producing a crate which is freely ventilated and which will, therefore, be particularly useful 20 for the transportation of live poultry, as well as produce of any kind which keeps best in a freely ventilated condition. The wings of the side members, the end members and the top member or any of said 25 wings may, however, be constructed of solid material when preferred.

In folding or collapsing the improved crate, it will be seen that the side members B, B' may be folded or collapsed on the 30 wings of the bottom member, which latter is then folded so that the wings of the two side members will be presented exteriorly of the wings of the bottom member. The lid or top member D may now be folded and collapsed on the top wing of the side member B' with which it is hingedly connected, and the end members, having first been folded, are now collapsed endwise on the side member B' with the upper wing of which 35 the upper wings of said end members are hingedly connected at the two ends thereof. A compact bundle will thus be produced, as best seen in Fig. 6, there being no waste 40 spaces, and the crate may, therefore, be stored and reshipped in the smallest possible space and at the least possible expense. It may be stated that in the practical manufacture of the crate it is preferred that the 45 height and width should be approximately equal and that the length be approximately 50 equal to the combined height and width, but these proportions may be departed from.

Having thus described the invention, what is claimed as new, is:—

55 1. A folding crate comprising a longitudinally divided bottom member, the wings of which are hingedly connected together, longitudinally divided side members, the wings of which are hingedly connected together, hinges connecting the lower wings 60

of the side members with the outer edges of the wings of the bottom members, longitudinally divided end members each consisting of hingedly connected upper and lower wings, hinges connecting the upper wings 65 of the two end members with the ends of the upper wing of one side member, a longitudinally divided top member comprising hingedly connected wings, and hinges connecting one wing of the top member with 70 the upper wing of the other side member.

2. A folding crate comprising a longitudinally divided bottom member, the wings of which are hingedly connected together, longitudinally divided side members, the 75 wings of which are hingedly connected together, hinges connecting the lower wings of the side members with the outer edges of the wings of the bottom members, longitudinally divided end members each consisting of hingedly connected upper and lower wings, hinges connecting the upper wings 80 of the two end members with the ends of the upper wing of one side member, a longitudinally divided top member comprising 85 hingedly connected wings, and hinges connecting one wing of the top member with the upper wing of the other side member; one wing of the top member being composed of two hingedly connected parts, one of 90 which constitutes an auxiliary lid.

3. A folding crate comprising a longitudinally divided bottom member, the wings of which are hingedly connected together, longitudinally divided side members, the 95 wings of which are hingedly connected together, hinges connecting the lower wings of the side members with the outer edges of the wings of the bottom members, longitudinally divided end members each consisting of hingedly connected upper and lower wings, hinges connecting the upper wings 100 of the two end members with the ends of the upper wing of one side member, a longitudinally divided top member comprising 105 hingedly connected wings, and hinges connecting one wing of the top member with the upper wing of the other side member; and fastening means whereby the upper wings of the end members may be detachably connected with the upper wing of the side member with which the top member is 110 hingedly connected.

In testimony whereof I affix my signature in presence of two witnesses.

IRA F. LAMP.
